United States Patent

Des. 237,826
Patented Nov. 25, 1975

237,826

TELEVISION RECEIVER

John B. MacDonald, 4004 Oak Drive, and Richard J.
Halstead, 2321 Drum Creek Road, both of Chesapeake,
Va. 23321

Filed Apr. 27, 1973, Ser. No. 355,040

Term of patent 14 years

Int. Cl. D14—03

U.S. Cl. D56—4 D

Fig. 1

FIG. 2

FIG. 3

Fig. 4

FIG. 5

FIG. 1 is a front, top and right side perspective view of a television receiver showing our new design;

FIG. 2 is a front elevational view;

FIG. 3 is a top plan view;

FIG. 4 is a right side elevational view, the left side being substantially a mirror image thereof; and

FIG. 5 is a rear elevational view.

The left and right sides of the television receiver are substantially identical.

We claim:

The ornamental design for a television receiver, as shown and described.
